UNITED STATES PATENT OFFICE.

DANIEL W. MILLSAPS, OF WASHINGTON, DISTRICT OF COLUMBIA.

PACKAGE-TIE.

1,360,969.

Specification of Letters Patent. Patented Nov. 30, 1920.

Application filed April 26, 1920. Serial No. 376,836.

To all whom it may concern:

Be it known that I, DANIEL W. MILLSAPS, a citizen of the United States, residing at Washington, District of Columbia, have invented new and useful Improvements in Package-Ties, of which the following is a specification.

This invention relates to package ties or binders and it is an improvement on the device of this class which Letters Patent of the United States, No. 1,006,584, were granted to me on October 24, 1911.

The device patented to me as above stated is a package binder for letters and the like comprising flat elastic straps adapted to extend around and closely embrace the package at right angles to each other and secured together at opposite sides, one of said straps being made in two parts, and one of said parts being pivotally connected to the other part whereby it may be turned to one side in flat condition without twisting or bending. The material used in the construction of this tie consists of flat elastic straps made of strips of rubber covered with and connected by a coating of textile material.

The present invention has for its object to improve and increase the resiliency and durability of the binder by constructing the same mainly of resilient metallic wire in a simple and improved way.

A further object of the invention is to simplify and improve the means whereby the metallic straps or bands are united together in such a manner as to permit the loop formed by one of said bands to be conveniently moved to a position at substantially right angles to its mate.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings:

Figure 1 is a plan view of a package of 55 letters having the improved binder applied thereto with dotted lines indicating how one of the loops may be moved to a releasing position.

Fig. 2 is a side view of the package showing the joint in section.

Fig. 3 is a perspective view of the binder removed.

Corresponding parts in the several figures are denoted by like characters of reference. 65

The improved binder is formed of four separate binding members 15, 16, 17, and 18, each of said members being formed of a wire spring which is longitudinally extensible, the wire of which said spring is composed being bent intermediate the ends thereof so as to form a plurality of V-shaped loops 19 having their apices disposed alternately in opposite directions, this structure being produced by bending the wire zigzag- 75 wise as will be readily understood. The purpose of forming the wire spring in this particular manner is to produce an absolutely flat formation the thickness of which does not at any point exceed the diameter 80 of the wire while the width of the structure may be varied by forming the limbs 20 of the individual V-shaped loops of the requisite or any desired length. Each of the binding members is bent at the ends thereof so as to 85 form an eye 21.

For the purpose of assembling the binding members in operative relation, two disks 22 are provided, each of said disks being provided at diametrically opposite sides thereof with apertures 23 that are engaged by the eyes 21 of the oppositely disposed binding members 15, 16. The eyes 21 of the third binding member 17 are engaged with apertures 24 in the disks 22 which are located midway between the apertures 23, the binding member 17 being thus located midway between and substantially at right angles to the binding members 15, 16. The binding member 18 is preferably, although not necessarily, made of greater length than the remaining members, and the eyes 21 of said member are slidably engaged with arcuate slots 25 formed in the disks 22 and extending from points diametrically opposite to the apertures 24 in the direction of the apertures 23 at one side of the disks. This will enable the member 18 to be readily moved to

a disengaged position as indicated in dotted lines in Fig. 1.

When the member 18 is in the disengaged position shown in dotted lines in Fig. 1 a package of cards, letters or the like, may be readily introduced between the members 15, 16, 17, the latter being of such great resiliency that they will readily adapt themselves to packages of greatly varying dimensions. By restoring the member 18 to the position shown in full lines in Fig. 1, the said member will be placed in longitudinal alignment with the member 17 and substantially at right angles to the members 15, 16, and letters or cards composing the package will thus be securely retained in assembled relation.

The springs entering into the construction of this device being absolutely flat and at no point of a thickness exceeding that of the wires of which they are formed, it is obvious that the improved binder will occupy very little space and will not at any point project materially beyond the sides of the package. The device being of entirely metallic construction the same will be found extremely durable and not liable to be injured by constant use. The invention, therefore provides an extremely simple, durable and inexpensive device for typing the assembled letters, cards and other objects for convenience in transportation or filing as may be required.

Having described the invention what I claim as new is:

1. A package binder embodying in its construction a plurality of members each formed of a longitudinally extensible flat wire spring, said spring being at no point of a thickness exceeding the diameter of 40 the wire of which it is formed.

2. A package binder embodying in its construction a plurality of wire members, each composed of a wire bent zigzag-wise to form a plurality of loops, the spring thus formed being at no point of a thickness exceeding that of the wire.

3. A package binder embodying in its construction a plurality of members, each formed of a flat longitudinally extensible wire construction, each member being provided at the ends thereof with eyes in combination with assembling disks having openings engaged by said eyes.

4. A package binder embodying in its construction a plurality of members, each formed of a flat longitudinally extensible wire construction, each member being provided at the ends thereof with eyes in combination with assembling disks having openings engaged by said eyes, the openings engaged by eyes of one of the members being in the nature of arcuate slots.

In testimony whereof I affix my signature.

DANIEL W. MILLSAPS.
